UNITED STATES PATENT OFFICE.

ZEALIA VAN RAALTE, OF NEW YORK, N. Y., ASSIGNOR TO S. OPPENHEIMER & LEVY, OF NEW YORK, N. Y., A FIRM.

TICKET FOR NET GOODS OR VEILINGS.

No. 893,039.

Specification of Letters Patent.

Patented July 14, 1908.

Application filed December 8, 1906. Serial No. 346,849.

To all whom it may concern:

Be it known that I, ZEALIA VAN RAALTE, a citizen of the United States, and a resident of the city, county, and State of New York, have invented certain new and useful Improvements in Tickets for Net Goods or Veilings, of which the following is a description.

The object of my invention is to provide a ticket for marking nets or veilings having a large mesh, which will remain close to the goods so as not to be troublesome, and which will engage the threads and be adapted to be removed without injuring the goods in any way.

In the drawings forming part of this application, Figure 1 is a plan view of a veiling with a ticket attached. Fig. 2 is a section on the line 2—2 of Fig. 1, and Fig. 3 is a plan view of a ticket before it is attached.

The ticket is adapted to be applied to a net or veiling 1, having a large mesh, and without use of pins or any means which will injure the threads when the ticket is removed. The ticket consists of a flat piece of paper 2, or other suitable material, which is bent into a loop 3, with some of the threads of the net included in the loop, so that the loop will be held thereby, and the free ends are secured together at 4, preferably by pasting. The ends of the paper are weakened, preferably by perforating, either before securing the

ends together or afterwards, so that the lines of weakening of each end will be together and so that the pasting will be beyond the 35 points of weakening. In the drawings the strip is shown weakened at the points 5.

When the ticket is on the goods, as is shown in Fig. 2, it is only necessary to tear the same on the line of weakening when the 40 ticket may be removed, without in any way affecting the net, the threads of which are very delicate.

Having described my invention, what I claim is:

The combination of a net fabric having an open mesh and means for marking the same, consisting of a strip of fabric doubled over upon itself so that the strip lies over and under the net, the bight of the loop thus formed 50 passing through one of the meshes of the fabric and the end of the under portion of said strip also passing through a mesh of the fabric and extending upwardly, the ends of said strip coinciding and being fastened together above the fabric and both ends being provided with a weakened portion at the point where the loop of said strip ends, substantially as described.

Signed this 1st day of December, 1906. 60
Z. VAN RAALTE.
